UNITED STATES PATENT OFFICE.

JOHN B. HADAWAY, OF BROCKTON, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING ON WELTS.

962,138.

Specification of Letters Patent. Patented June 21, 1910.

Application filed May 29, 1902. Serial No. 109,505.

To all whom it may concern:

Be it known that I, JOHN B. HADAWAY, a citizen of the United States, residing at Brockton, in the county of Plymouth and 5 State of Massachusetts, have invented certain new and useful Improvements in Machines for Operating on Welts; and I do hereby declare the following to be a full, clear, and exact description of the invention, 10 such as will enable others skilled in the art to which it appertains to make and use the same.

The present invention relates to a machine for operating on welts.

15 In the manufacture of welted shoes, the welt after being attached to the shoe is subjected to a beating out operation in order to cause it to lie flat in substantially the plane of the insole. To facilitate the beating out operation the welt is usually slitted or slashed at certain points and particularly at the toe portion of the shoe. The slitting or slashing of the welt has usually 20 been performed by means of a hand knife after the welt is attached to the shoe and 25 before the shoe is presented to the welt beating machine.

The object of the present invention is to provide a simple and efficient machine for 30 operating upon welts by which a series of slits can be quickly formed in a welt in a certain and satisfactory manner and the welt thereby prepared for the operation thereon of the welt beating hammer or other tool of 35 a welt beating machine.

With this object in view, the present invention consists in the devices, combinations, and arrangements of parts herein- 40 after described and claimed, the advantages 45 of which will be obvious to those skilled in the art from the following description.

The invention is intended primarily as an improvement in welt beating machines, the means for slitting the welt being associated 45 with means for beating out the welt so that the welt is slitted and beaten out at one operation. Certain features of the invention are, however, applicable to a machine for operating upon a welt after attachment 50 to the shoe which does not embody means for beating out the welt. Certain features of the invention are also applicable to a machine for operating upon a welt or strip of welt material before being attached to a 55 shoe to prepare the welt for easy applica-

tion to the shoe or for the efficient operation thereon of a welt beating machine, and as to these features the invention, except as defined in the claims, is not limited to a machine adapted for operation upon a 60 welt after being attached to a shoe.

In the accompanying drawings illustrating one form of my invention Figure 1 is a side elevation; Fig. 2 is a front elevation; Fig. 3 is a plan of the complete machine; 65 Figs. 4 and 5 are respectively a rear elevation and plan of the beating out and feeding wheel; Figs. 6 and 7 are respectively an elevation and section of a portion of the welt slitting wheel; Figs. 8 and 9 are 70 respectively a front elevation and side elevation of the body of the welt slitting wheel; Figs. 10 and 11 are respectively a side elevation and edge view of a welt slitting knife; and Fig. 12 is a sectional side elevation of the beating out and feeding wheel 75 in connection with the welt slitting wheel showing the co-operative relation of the two.

The illustrated embodiment of my invention consists, in general, of means for supporting the welt, means for beating out and feeding the welt and means for slitting the welt, together with means for throwing the welt slitting means into and out of operation during the continued operation of the 85 beating out and feeding means.

Referring to the drawing the means for supporting the welt consists of a rotatable work support 1, constructed to enter the crease between the upper and welt and to 90 support the welt for operation thereon by the beating out and feeding means and welt slitting means; it is mounted on a stud projected upward from the base 2, provided on its under side with a tongue and groove connection with the slotted arm 3 projected forward from the frame 4 of the machine. A bolt 5, passing through the slot in the arm 3, serves to hold the base 2 in adjusted position thereon.

The means for beating out and feeding the welt consists of the wheel 6, shown in detail in Figs. 4 and 5 which is splined on the front end of the main shaft 7 of the machine, being held in place by a nut which 105 holds said wheel against a shoulder near the end of the shaft. The surface of the beating out and feeding wheel 6 is scored or roughened to enable it to obtain an efficient grip on the welt for feeding the same. The op- 110

erating surface of the roll 6 is normally held in such position with relation to the work support that when the shoe is presented to the machine the roll bears with pressure upon the welt thereby beating out and feeding the same during the operation of the machine. The main shaft 7 is mounted in suitable bearings in the swinging arm 8 pivoted at 9 between the ears 10 projected upward from the rear part of the frame 4 of the machine. The swinging arm 8 is held from lateral deflection at its front end by the ears 11 projected upward from the front part of the frame of the machine between which ears the swinging arm 8 is adapted to slide vertically. Springs 12 are employed normally to pull the swinging arm 8 downward, such springs being mounted on rods 13 extended through slotted ears 14 projected out from the frame 4 of the machine and attached to opposite sides of the front end of the swinging arm 8 by bolts screwed into bosses projected from such arm, adjusting nuts 15 being screwed on the lower ends of such rods for adjusting the pressure of the springs against the nuts so that the downward pull exerted by the springs on the swinging arm 8 can be regulated whereby the pressure of the beating out and feeding wheel upon the welt may be varied. Stop collars 16 are adjustably secured to the rods 13 above the ears 14 to limit the downward motion of the swinging arm so that the knives of the welt slitting wheel shall not come in contact with the work support. A lever 17, pivoted at 18 to the frame 4 of the machine, bears with one end upon the underside of the front end of the swinging arm and to its other end is attached a rod 19 running down to a suitable treadle (not shown), affords means of raising the front end of the swinging arm, and thereby of raising the beating out and feeding wheel 6, so that the work may be conveniently entered between the wheel 6 and work support 1.

The beating out and feeding wheel 6 has two functions, one that of beating out the welt, and the other, that of feeding the welt, and such wheel may be regarded, therefore, either as means for beating out the welt, or as means for feeding the welt, or both. In some of the claims I have included as an element, means for beating out the welt by which I intend to define as an element of such claims any suitable means for beating out the welt without limiting such element to the specific forms illustrated in the drawings and irrespective of whether such beating out means has the additional function of feeding the welt or not. In other claims I have included as an element means for feeding the welt by which I intend to define as an element of such claims means for feeding the welt without limiting

such element to the specific form illustrated in the drawings and irrespective of whether such welt feeding means has the additional function of beating out the welt or not.

The means for slitting the welt consists of the welt slitting wheel, indicated in a general way by the reference character 20. The welt slitting wheel 20 consists of a body 21 provided with radial slits 22 which receive the shanks of knives 23. The shanks of the knives are wider than the slots 22 and project out beyond the same and are engaged on their projecting edges by a plate 24, which is provided with a series of projecting teeth which engage corresponding teeth on the projecting edges of the knives, which plate 24 is screwed onto a boss on the body 21, whereby the knives are securely held in place and at the same time are capable of being adjusted in and out to regulate the distance that they shall project out beyond the surface of the body 21. The cutting edges of the knives lie in planes including the axis of the shaft 7 and the main portion of such cutting edges also lie in the surface of a cone whose apex is in the said axis prolonged beyond the front end of the shaft 7 so that the cuts made by the knives in the welt taper in depth from the outer edge of the welt toward the inseam stitch receiving portions thereof. The body 21 is slidably mounted on the shaft 7 but is splined thereto so as to be held from rotation with relation thereto, and a groove 25, in the reduced portion 26 of the body 21, receives a fork 27 by means of which the body 21 may be moved longitudinally of the shaft 7. In Figs. 1, 3 and 12 of the drawings the welt slitting means or wheel 20 is shown at the limit of its forward movement. The beating out and feeding wheel 6 is provided with a rearwardly projected rim 28 which is slotted to receive the ends of the knives 23 which project outwardly beyond the outer surface of the body 21 of the wheel 20, such body 21 being smaller than the cavity in the rear side of the wheel 6 formed by the rim 28 so that the said body 21 may be received in said cavity when it is moved to its forward position as shown in the figures above referred to. The sides of the slots in the rim 28 afford support for the projecting ends of the knives 23 when the wheel 20 occupies its forward or operative position. In order that the welt may be slit only at those portions where it is necessary or desirable to slit the welt to enable it to be readily beaten out flat means are provided for moving the wheel 20 into and out of operative position during the continued operation of the beating out and feeding wheel 6, such means consisting of the fork 27, above referred to, which is mounted on the forward end of a reciprocable slide 29 mounted in suitable bearings 30, integral with, or se-

cured to; the swinging arm 8, which slide is provided with a cam roll 31, which engages a cam slot 32 in the lever 33 pivoted at 34 on the side of the rear part of the frame 4. 5 a rod 35 being connected to said lever and extending downward to a treadle (not shown) by means of which the lever 33 may be depressed against the action of the spring 36 secured at one end to the lever 33 10 and at the other end to the swinging arm 8 by means of which the lever 33 is normally held in raised position, so that when the lever 33 is depressed by the treadle connected to the rod 35, the cam roll 31 on the side of 15 the slide 29 will be moved by the slot 32 forward, thereby moving the welt slitting wheel into the position illustrated in the drawing. When the foot is lifted from the treadle the spring 36 will pull back the slide 20 29 thereby withdrawing the welt slitting wheel from operative position. The upper portion of the slot 32 receives the stud 38 secured to the side of the swinging arm 8. The slot 32 is of such a length that the end 25 of the slot engages the stud 38 when the lever 33 is depressed to the extent of moving the slide 29 to the limit of its forward movement and pressure then exerted upon the treadle connected to the rod 35 is transmitted to the pin 38 whereby an additional 30 pressure is exerted upon the swinging arm beyond that which is exerted by the springs 12 which operates to press the beating out and feeding wheel 6 with greater pressure 35 against the welt. Thus during the time the welt slitting knives are in operation, as during the slitting around the toe of a boot or shoe, the pressure of the beating out and feeding wheel 6 upon the welt is increased 40 at the time when the greatest pressure is necessary for this purpose as it is well known that more beating out is required, or greater pressure is required, to beat out the portion 45 of the welt extending around the toe of a boot or shoe.

In some of the claims I have used the expression means for slitting the welt by which I intend to define as an element of such claims any suitable means for slitting the 50 welt without limiting such element to the specific form illustrated in the drawings as any means for slitting the welt is within the purview of my invention, viewed in its broader aspects.

55 The driving means provided for driving the beating out and feeding wheel 6 and welt slitting wheel 20, consist of the main shaft 7 which is provided upon its rear end with a gear 39 which meshes with a pinion 40 mounted upon auxiliary shaft 41 which is fixedly secured to the rear part of the frame 4. A fast pulley 42 is secured to the sleeve 43 formed integral with or secured to the gear 40 and the loose pulley 44 is loosely 50 mounted upon the shaft 41 along side of the

fast pulley 42 onto which the belt may be moved when it is desired to stop the machine.

In an application filed October 19, 1903, Serial No. 177,587, I have disclosed and broadly claimed a machine for operating on welts after attachment to a shoe comprising means for beating out the welt and means for slitting the welt, and in an application filed May 26, 1902, Serial No. 109,018, I have disclosed and claimed a machine for operating on welts either before or after attachment to a shoe comprising means for beating out the welt, means for feeding the welt, and means for slitting the welt. I do not desire to claim herein anything disclosed in the applications above referred to, but

Having described my invention, I claim as new and desire to secure by Letters Patent of the United States:

1. A machine for operating on welts, having, in combination, means for supporting the welt, means for beating out the welt, means under the control of the operator for increasing the pressure of the beating out 90 means during the continued operation of the machine, substantially as described.

2. A machine for operating on welts, having, in combination, means for supporting the welt, means for beating out the welt, 95 means for slitting the welt, and means for throwing the welt slitting means into and out of operation during the continued operation of the welt beating means, having provision for increasing the pressure of the beating out means upon the welt when the welt slitting means are in operation, substantially as described.

3. A machine for operating on welts, having, in combination, feeding means, welt slitting means, means for throwing the welt slitting means into and out of operation during the continued operation of the feeding means, having provision for increasing the pressure of the feeding means upon the welt 110 when the welt slitting means are in operation, substantially as described.

4. A machine for operating upon welts, having, in combination, a work support, a feeding wheel provided with slots, a series of 115 welt slitting knives adapted to be projected into said slots and withdrawn therefrom and means for moving the welt slitting knives to project them into and withdraw them from the slots, substantially as described.

5. A machine for operating upon welts, having, in combination, a main shaft, a beating out and feeding wheel secured to the end of said shaft, a stationary work support 125 located adjacent to the surface of the beating out and feeding wheel, and a plurality of welt slitting knives acting to slit the welt, substantially as described.

6. A machine for operating upon welts,

- 4
- having, in combination, a work support, a beating out and feeding wheel, a shaft for supporting said wheel, means for rotating said shaft, a spring normally forcing the 5 beating out and feeding wheel toward the work support, and means for slitting the welt, substantially as described.
7. A machine for operating upon welts, having, in combination, a work support, 10 means for beating out the welt, and a welt slitting wheel provided with knives for slitting the welt, substantially as described.
8. A machine for operating upon welts, having, in combination, a work support, 15 means for beating out the welt, a welt slitting wheel provided with a plurality of knives for slitting the welt, means for throwing said welt slitting wheel into and out of operation, substantially as described.
- 20 9. A machine for operating upon welts, having, in combination, a welt beating wheel, welt slitting means, and means for throwing the welt slitting means into and out of operation during the continued operation of the 25 welt beating wheel, substantially as described.
10. A machine for operating upon welts, having, in combination, welt beating means, welt slitting means, a slide for throwing the 30 welt slitting means into and out of operation, and a slotted lever for actuating the slide, substantially as described.
11. A machine for operating upon welts, having, in combination, a work support, 35 welt beating means, means for pressing the welt beating means toward the work support with yielding pressure, welt slitting means, a slide for moving the welt slitting means into and out of operation, a pivoted 40 lever provided with a slot, such slot acting upon the slide to move the welt slitting means into operation and to cause the welt beating means to exert an increased pressure upon the welt, substantially as described.
- 45 12. A machine for operating upon welts having, in combination a frame, a work support fixedly secured to said frame, a swinging arm provided with a pin pivotally secured to said frame, a beating out wheel, a 50 shaft carrying said beating out wheel mounted in bearings in said swinging arm, a spring connected to said swinging arm and acting normally to move the beating out wheel toward the work support, a welt slitting wheel also mounted upon said shaft, a 55 slide for moving said welt slitting wheel into and out of operation, said slide being provided with a cam roll, a slotted lever pivotally supported upon said frame, said slot being 60 adapted to receive the cam roll on the slide and the pin on the swinging arm acting when moved to throw the welt slitting wheel into operation and to exert a pull upon the swinging arm to increase the pressure upon 65 the welt, substantially as described.
13. A machine for operating upon welts, having, in combination, a work support, a beating out and feeding wheel, a welt slitting wheel, a shaft upon which said wheels are mounted, a swinging arm provided with 70 bearings to receive said shaft, yielding means for moving the swinging arm in the direction to move the beating out and feeding wheel and welt slitting wheel toward the work support, and means for lifting said 75 swinging arm to enter the welt, substantially as described.
14. A machine for operating upon welts, having, in combination, a work support, 80 means for beating out the welt, means for slitting the welt, yielding means normally tending to withdraw the welt slitting means from operation, and means under control of the operator for holding the welt slitting means in operation, substantially as de- 85 scribed.
15. A machine for operating upon welts, having, in combination, a beating out wheel, a welt slitting wheel provided with knives for slitting the welt, and a work support 90 arranged to support the welt in position to be acted upon by each of said wheels, substantially as described.
16. A machine for operating upon welts, having, in combination, a beating out wheel, 95 a plurality of welt slitting knives acting to slit the welt, and a work support arranged to support the welt in position to be acted upon by said wheel and knives, substan- 100 tially as described.
17. A machine for operating upon welts after attachment to the shoe, having, in combination, a work support shaped to support the projecting edge of the welt, means for slitting the welt, means for feeding the shoe 105 to present successive portions of the projecting edge of the welt to the slitting means, and means for throwing the welt slitting means into and out of operation during the continued operation of the feeding means, 110 substantially as described.
18. A machine for operating upon welts after attachment to the shoe, having, in combination, a work support shaped to support the projecting edge of the welt, means for 115 slitting the welt, means for beating out the welt and for feeding the shoe to present successive portions of the projecting edge of the welt to the welt slitting means, and means for throwing the welt slitting means 120 into and out of operation during the continued operation of the beating out and feeding means, substantially as described.
19. A machine for operating upon welts, having, in combination, a work support 125 shaped to support the welt of a welted shoe, a feed wheel provided with slots, a series of welt slitting knives adapted to be projected into said slots and withdrawn therefrom, and means for moving the welt slitting 130

knives to project them into and withdraw them from the slots, substantially as described.

20. A machine for operating upon welts, having, in combination, means for feeding the welt, a welt slitting wheel provided with knives for slitting the welt, and means for throwing the welt slitting wheel into and out of operation during the continued operation of the feeding means, substantially as described.

21. A machine for operating upon welts, having, in combination, means for supporting the welt, a welt slitting wheel provided with knives for slitting the welt, and means for throwing the welt slitting wheel into and out of operation, permitting a continued

movement of the welt while the welt slitting wheel is out of operation, substantially as described.

22. A machine for operating upon welts, having, in combination, a welt feeding wheel, a welt slitting wheel provided with knives for slitting the welt, and means for throwing the welt slitting wheel into and out of operation during the continued operation of the welt feeding wheel, substantially as described.

In testimony whereof I affix my signature, in presence of two witnesses.

JOHN B. HADAWAY.

Witnesses:
